SPIRAL TRACK DEVELOPING TANK

Verneur E. Pratt and George F. Gray,
Norwalk, Conn.

Application May 18, 1945, Serial No. 594,506

2 Claims. (Cl. 242—77)

1

This invention relates to spiral track developing tanks of the type used for developing, fixing and washing strips of film. Such tanks comprise a tank or receptacle in which there are members or plates spaced apart and having spiral grooves in their opposed surfaces in which the film is wound. These form a spiral track for the film whereby it is coiled within the carrier formed by the plates and with its convolutions spaced apart.

While liquids can be poured into such tanks in the daylight, the film must be inserted in the carrier in the dark room or in dim light depending on the sensitivity of the emulsion. In tanks using known forms of carriers the user must push or lay the film into the spiral grooves in the plates, working in the dark.

In some models the carrier comprises a pair of plates carried on a central shaft which positions the plates with their opposed grooves properly spaced to receive the film. A hook is furnished on the central shaft to which the inner end of the film can be affixed, in order that the user can then lay the film in the grooves; but in most of the tanks the long, limber length of film must be pushed into the grooves.

Pushing the film into the grooves is difficult enough when the tank is new and the grooves are dry and clean; it becomes more difficult and often impossible when the grooves become covered with the products of development and are abrasively coated with silver deposit, or when the grooves are not completely dried and the surface tension of the water left in the grooves acts to retard the insertion of the film.

On the types of spiral-wound tanks which presume that the user will "lay" the film in the grooves, it has been found that even after much practice in the dark, the average user makes mistakes and too often the successive layers of film are not adequately separated in the grooves, with the result that the film touches and developing and fixing are incomplete to the extent that too often the images are lost.

An object of the instant invention is to furnish a spiral track carrier into the grooves on which the film is pulled rather than pushed or laid.

Another object is to provide a carrier of the type described in which the film can be pulled, which is adjustable to take film of various widths.

Another object is to provide a film carrier of the type described in which the film may be pulled into the groove when the same are wet and where a considerable length of film can be pulled into the grooves with ease regardless of the condition of the grooves.

2

Other objects of the invention will be apparent from an examination of the following specification and drawings.

In the accompanying drawings:

5 Figure 1 is a vertical view partly in section of the feed fingers and one of the plates of a film carrier embodying this invention and taken on the line 1—1 of Figure 2;

10 Figure 2 is a vertical sectional view of a film carrier embodying the invention;

Figure 3 is a view on the line 3, 3 Figure 1 looking down on the shaft 14 shown in Figures 1 and 2 and showing the parts 24 and 30 in section;

15 Figure 4 is a front view of the device shown in the preceding figures with one of its feed fingers 30 in extended position;

Figure 5 is an enlarged rear view of the feed fingers 24 and 30;

20 Figure 6 is a slightly enlarged sectional view on the line 6—6 of Figure 5;

Figure 7 is a view partly in section on the line 7, 7 of Figure 8 showing an alternate type of feed finger but showing both plates 10 and 11 of the device;

25 Figure 8 is a view partly in section on the line 8—8 of Figure 7.

Referring to Figures 1 and 2 the numerals 10—11 indicate the usual pair of plates used in film carriers having therein respectively the continuous spiral grooves 12—13; these grooves begin as shown for the groove 13 at 13b, on the outer periphery of the plates and continue inwardly to a point adjacent the shaft 14.

The shaft 14 together with its knob and nuts is usually sufficient to hold the plates together without wobble when assembled as hereinafter described. But, in order to prevent the plates from having any relative turning movement the plate 10 may be equipped with three pins one of which is shown at 15 which fit corresponding holes in plate 11. This arrangement permits the plates to be separated laterally to take film of different widths but does not allow the plates to revolve around the shaft 14 independently of each other.

50 Permanently secured to the shaft 14 is the knob 16. The shaft extends inwardly through a bearing 17 in plate 10 and then across a space 18 between the inner surface of the plates. From the inner surface of plate 11 and outwardly therefrom the shaft 14 is threaded as shown at 19. On this threaded portion is placed a nut 20 which may be turned to vary the width of the space 18 and consequently permit the processing of film of different widths. A lock nut

21 engages the external threads on nut 20 and an additional lock nut 22 may be brought up against the outer end of 20 as shown so that all three nuts 20, 21 and 22 are locked to the shaft 14 so as to revolve therewith. It will be seen that this shaft can be turned while the plates 10 and 11 are held stationary and properly spaced apart thereon.

The shaft 14 has a square hole 23 therein adapted to receive the feed finger 24 which is freely slideable in this hole. This feed finger extends upwardly, the upper end of same as shown in Figure 2 having an L-shaped extension 25 thereon which extends into the spiral groove 13 in plate 10. This extension 25 has a small upstanding lip 26 adapted to provide a seat or space between the inner edge 27 of the groove 13 and the film 28.

In the upper end of the feed finger 24 is provided one or more teeth 29 which project forward at an angle in the direction of the travel of the feed finger as best seen in Figure 1 and which are adapted to catch and hold the end of the film 28 when the finger is moved clockwise, Figure 1.

Now by engaging the film 28 on these teeth and rotating the knob 16 to rotate the finger 24 between the plates, the film 28 may be drawn into the grooves 12 and 13. As this occurs the end 25 of the feed finger 24 gradually progresses inwardly toward the shaft 14, the feed finger 24 sliding through the opening 23 therein. The film 28 is therefore pulled into the grooves 12 and 13 without any care or attention on the part of the operator and is coiled between the plates with its convolutions held apart by the grooves therein.

It will be understood that the total diameter of the device is such that ample room is provided between the last or inner convolutions of the grooves indicated at 12a in Figure 2, so that the inner end of the finger 24 in the space 18 will have room in which to travel without encountering any film that has been drawn into the device.

It will be observed that the right hand edge 28a of the film 28, Figure 2, extends to the right out beyond the edge 24a of the feed finger 24, but this is not found to be objectionable as the film is laterally quite stiff and if guided into the left hand groove 13 it is stiff enough to guide itself properly in the right hand groove 12.

Where the film is comparatively wide or very thin, it may be necessary to guide the right hand edge 28a just referred to. To accomplish this the auxiliary feed finger 30 is provided. This finger 30 lies in a sunken or cut out pocket 31 on the rear side of the feed finger 24.

For 16 mm. or other comparatively narrow film the auxiliary feed finger is placed with its short end 30a projecting to the right as shown in Figure 2, this end having the upstanding lip 30b corresponding to the lip 26, the film being positioned between the lips as shown. The auxiliary finger is secured in the pocket 31 of the finger 24 by means of a screw 32.

In order to provide for the use of wider film the auxiliary feed finger 30 may be turned so that the long arm 30d thereof will project to the right. This has upstanding lip 30c same as the lip 26 previously described and may be equipped with a plurality of teeth 30f for the purpose of engaging and holding the film.

Obviously when the auxiliary feed finger is used the plates 10 and 11 are separated the

necessary distance which is accomplished by adjusting the nuts 20, 21, 22 on shaft 14 as previously described.

It will be seen that the auxiliary feed finger 30 has two positions in which it may lie in the cavity 31. In one position the short arm 30a extends outwardly from finger 24, and in the other position the long arm 30d extends outwardly therefrom, and by means of the screw 32 the auxiliary finger may be locked to the feed finger 24 in either position.

As shown in Figure 6 the auxiliary finger 30 lies in the cavity 31 and there is an upstanding wall 24a along one of the outer edges of 24, the arrangement being such that when the feed fingers have been pulled inwardly, that both said fingers will ride through the square opening 23 in the shaft 14 as best seen in the sectional view Figure 3.

As is customary with these film carriers, the plates 10 and 11 and the shaft 14 may have holes or slots therein to permit the free circulation of liquid around and about the film in all directions in order to enable the liquids to reach all of the film simultaneously thereby preventing spotty development etc.

Instead of the feed finger arrangement previously described any other suitable arrangement can be used for pulling the film into the slots. Such an arrangement is shown in Figure 7. A spring member 33 is secured to the upper end of the feed finger 34 which is the same as the feed finger 24 of Figure 3 except that it tapers off to a comparatively narrow width at the top as indicated at 34a Figure 8 and is embraced by the inner U-shaped bend 33a of the member 33 which is secured thereto by means of a screw 35. The upper end 34a of the feed finger has claws 36 to engage the film 37.

As the member 33 is resilient the outwardly extending jaws that ride in the grooves 12, 13 being sprung outwardly, the plates 10, 11 can be brought together or spaced apart and the outer ends of member 33 will continue to ride in the grooves in these plates and guide the feed finger and film in the grooves as previously described.

The operation of the device is of course the same regardless of what type of feed finger is used therein.

It is believed that the operation of the device will be self-evident from the foregoing description, but it may be pointed out that the side 10 having the shaft 14 therein, may be laid upon a table in the dark room, and the end of the film 28 may be brought in through the mouths such as 13b of the groove 13 and impaled on the teeth 29 of the feed finger. The side plate 11 is now slipped over the pins 15 and is brought against the nut 20 which has been suitably adjusted along the threaded shank 19 of the shank 14 to provide a proper space at 18 for the film being used. After the side plate 11 is placed in position, the nut 21 is placed against the nut 20 and the locking nut 22 is placed in position as best shown in Figure 2.

If now the device is held in one hand and shaft 14 is rotated with the other, the film 28 will be gradually drawn into the continuous spiral grooves 12, 13, and will be held between the side plates 10 and 11 in a spiral form having its sensitive surfaces spaced apart by reason of the manner in which it is held.

It will also be seen that as the inner end of the feed finger 24 moves through the opening 23 in shaft 14, that by properly proportioning the

distance between the inner-most turn of the spiral groove and the shaft, that the said inner end of the member 24 will not encounter the inner convolution of the film, or in fact, touch the film in any way.

It will also be observed that adjustments necessary to accommodate various widths of film can be made before the device is taken into the dark room, and that the only manipulation of the device in the dark room is to place the starting end of the film on to the teeth of the feed finger, then bring the plates 10, 11 together, and finally tighten the nuts 21, 22 finger-tight.

What is claimed is:

1. In a device of the character described, members having complementary spiral grooves on their opposed faces when held in spaced-apart relation, a shaft passing through said members and revolvable therein, said members being adjustable along said shaft to vary the distance between their opposed faces, means for locking said members in the desired adjusted position, a feed finger slidable through said shaft and supported thereby, and engaging at least one of said grooves whereby said finger will be guided in said groove when said shaft is revolved in said members, said finger being adjustable to span the distance be-

tween said members, and means on said finger to engage and carry film into said grooves when said members and shaft are relatively moved.

2. In a device of the character described, means including opposed members forming a spiral track therebetween adapted to receive and hold a film by its edges, said members being axially adjustable to vary the distance between them, a shaft positioned adjacent the inner end of said track, and a feed finger slidably engaging said shaft and track and adapted to feed film into said track upon relative movement of said track and finger, said feed finger being adjustable to span the distance between said opposed members.
